UNITED STATES PATENT OFFICE.

ROBERT LEE GREEN, OF JACKSON, MICHIGAN.

CUSPIDOR-HOLDER.

1,101,509.

Specification of Letters Patent. Patented June 23, 1914.

Application filed November 20, 1913. Serial No. 802,141.

To all whom it may concern:

Be it known that I, ROBERT L. GREEN, a citizen of the United States, residing at Jackson, in the county of Jackson and State of Michigan, have invented certain new and useful Improvements in Cuspidor-Holders; and I do declare the following to be a full, clear, and exact description of the invention, such as will enable others skilled in the art

10 to which it appertains to make and use the same.

This invention relates to improvements in holders or stands for cuspidors, especially paper cuspidors.

15 The object of the invention is to provide simple, efficient and inexpensive means for supporting cuspidors and more especially sanitary cuspidors composed of paper or other suitable material which may be removed and burned or otherwise destroyed. With these and other objects in view the invention consists of certain novel features of construction, combination and arrangement of parts as will be hereinafter more 20 fully described and claimed.

25 In the accompanying drawing: Figure 1 represents a perspective view of a cuspidor holder constructed in accordance with this invention, with a cuspidor in operative position therein. Fig. 2 is a central vertical section thereof.

30 In the embodiment illustrated a supporting base is shown comprising an outer plate 1 of metal or other sanitary material which 35 may be readily cleansed, and having an inverted peripheral flange 2 which forms a housing to receive a suitable filler 3. A socket 3' is disposed centrally of said base and is here shown in the form of a small inverted cone having an inverted T-shaped securing element 4 fixed to the apex thereof and embedded in the material of the filler 3. A plurality of upright supporting rods as 40 are secured at one end by any suitable means 45 to said base 1 near the periphery thereof. An annular member 6 is secured to the upper ends of said rods 5 and is preferably constructed of stiff wire to form a reinforcing member for the upper edge of an inverted cone-shaped receptacle 7, said edge being 50 rolled around said wire as is shown clearly in Fig. 2. The apex of this inverted cone-shaped member 7 is mounted in the socket 3' which holds the lower end of said receptacle 55 against lateral movement. This receptacle 7 is designed to receive an inverted cone-

shaped cuspidor 8 composed of glazed paper or other similar cheap material, and which is provided at its upper end with an in-turned flange 9 which inclines downwardly 60 toward the central opening 10 therein to direct the saliva and other matter into the body of the cuspidor. This flange 9 may be integral with the body of the cuspidor or not as desired.

65 An annular plate 11 is designed to fit over the upper end of the cuspidor for holding it against vertical displacement. This plate 11 is provided on its outer edge with a depending flange 12 which fits over the rolled edge of the receptacle 7 and is secured in operative position by a plurality of spring gripping tongues or fingers 13 formed by slitting the edge of the flange 12 transversely as shown at 14 and bending the material between the slits inward as is shown clearly in Fig. 2. This plate 11 is also inclined downwardly toward its inner edge to adapt it to snugly fit the outer face of the flange 9 of the cuspidor.

70 From the foregoing description taken in connection with the accompanying drawings, the construction and operation of the invention will be readily understood without requiring a more extended explanation.

75 Various changes in the form, proportion and the minor details of construction may be resorted to without departing from the principle or sacrificing any of the advantages 80 of this invention as defined in the appended 85 claims.

I claim as my invention:

1. A cuspidor holder comprising a base plate, a plurality of uprights secured to said plate, said plate having a centrally disposed socket, an inverted cone-shaped member having its apex mounted in said socket and its upper end secured to said uprights, and an annular plate fitting over the upper end of said inverted cone-shaped member.

90 2. A cuspidor holder comprising a base plate, a plurality of uprights secured to said plate, said plate having a centrally disposed socket, an inverted cone-shaped vessel having its apex mounted in said socket, a ring connecting the upper ends of said uprights, said vessel having its upper edge rolled around said ring, and an annular plate mounted on the upper end of said vessel and having a depending peripheral 100 flange.

105 3. A cuspidor holder comprising a base

plate, a plurality of uprights secured to said plate, a wire ring connecting the upper ends of said uprights, an inverted cone-shaped vessel having its apex engaging said plate, and its upper edge rolled around said wire ring, and an annular plate mounted on the upper end of said vessel and having a depending peripheral flange having indent tongues for connecting said plate to 10 said vessel.

4. A cuspidor holder comprising a base plate, an inverted cone-shaped socket disposed in said base plate and having an inverted T-shaped securing element, uprights secured to said plate and an annular member connecting said uprights.

5. A cuspidor holder comprising a base plate having an inturned peripheral flange, a filler disposed in said plate, an inverted cone-shaped socket disposed in said base-plate and having an inverted T-shaped securing element fixed to the apex thereof and embedded in said filler, uprights secured to said plate and an annular member connect- 25 ing said uprights.

In testimony whereof I have hereunto set my hand in presence of two subscribing witnesses.

ROBERT LEE GREEN.
